UNITED STATES PATENT OFFICE.

EMIL POUYAT, OF LIMOGES, FRANCE.

DESIGN FOR A DISH.

SPECIFICATION forming part of Design No. 19,741, dated April 1, 1890.

Application filed December 23, 1889. Serial No. 334,794. Term of patent 14 years. Registered in France October 14, 1889, No. 279.

To all whom it may concern:

Be it known that I, EMIL POUYAT, a citizen of France, residing at Limoges, in the Department of Haute-Vienne, France, have invented and produced a new and original Design for Dishes, of which the following is a specification, reference being had to the accompanying drawings, forming a part thereof.

Figure 1 is a profile view of a soup-tureen or covered dish. Fig. 2 is a face view of a cover. Fig. 3 is the face view of a platter or deep dish. Fig. 4 is the face view of a plate, these four drawings being deemed necessary to fully illustrate my design.

15 The leading feature of my design consists in having seven curved and spreading rays A A A A start from the top of the dish and pass over the four corners, ending at the base of the dish.

20 The form of the soup-tureen or covered dish, Fig. 1, is oval. From the top of the cover near where the ends of the handle join the piece a set of seven curved and spreading rays A A A A follow the dish over each of the four corners and down the body of the dish to its base. The handles B B B, as more clearly shown in Fig. 2, are twisted acanthus-leaves. At the extremities of the handle and

where they join the piece is fastened a bouquet of Marguerites, leaves, buds, and flowers C C. 30

The platters or deep dishes, Fig. 3, are also of oval form; but the handles B B are in relief and have the same decoration as the soup-tureen or covered dish. At the four corners, passing down from the outside circumference toward the center or basin of the dish, are seven curved and spreading rays A A A A. 35

The plates, Fig. 4, are round, and from the center of the basin D start out in three directions seven curved and spreading rays, 40 which end at the outside circumference E, where they give the plate a scalloped appearance.

What I claim is—

1. The design for dishes herein shown and described. 45

2. In the design for dishes herein shown and described, the handles consisting of a representation of acanthus-leaves, and at the extremities of the handles where they join the piece a bouquet of Marguerites, leaves, buds, and flowers. 50

EMIL POUYAT.
